UNITED STATES PATENT OFFICE.

ISAAC E. BLAKE AND HERMAN RAUCHFUSS, OF DENVER, COLORADO.

HYDROCARBON-BURNER.

SPECIFICATION forming part of Letters Patent No. 453,335, dated June 2, 1891.

Application filed April 17, 1890. Serial No. 348,300. (No model.)

To all whom it may concern:

Be it known that we, ISAAC E. BLAKE and HERMAN RAUCHFUSS, citizens of the United States, residing at Denver, county of Arapahoe, and State of Colorado, have invented certain new and useful Improvements in Hydrocarbon Illuminating Burners, which are fully set forth in the following specification, reference being had to the accompanying drawings, forming a part thereof.

Figure 1 is a side elevation of our improved burner. Fig. 2 is a vertical axial section through the line 2 2 on Fig. 3, said Fig. 3 being a plan with the shield removed. Fig. 4 is a section at 4 4 on Fig. 1.

This application is for an invention related to another invention for which our joint application, Serial No. 348,301, is filed simultaneously herewith, and we do not design in this application to claim specifically anything which is shown in the other application above named.

This invention is designed to facilitate the use of hydrocarbon oils for illumination, and is adapted for use with the lighter and more volatile oils—such as naphtha or gasoline—which vaporize at a moderate heat.

It consists in improved devices whereby a minimum flame is maintained and protected from extinguishment and converted into a maximum flame when desired. The devices employed are designed also to make the maximum flame consist of radiating jets rather than a continuous integral flame.

In the drawings, A is the supply-tube and vaporizing-chamber, which is filled with any suitable absorbent and porous substance A', which checks the flow of the fluid to the burner and retains the heat after the burner is lighted, causing the fluid which is conducted into it to be vaporized in its pores. The tube or stem A is cast in one piece with or brazed at the upper end to the burner-tip B. Two ducts B' and B² extend through the burner-tip from the chamber in the stem A to the spreading-chamber B³, formed in the upper end of the burner-tip B. This spreading-chamber might properly also be called a "vaporizing-chamber," since before the burner becomes hot enough to cause the formation of vapor in the stem A the liquid will be vaporized in this spreading-chamber B³. Fine orifices b³ lead from the chamber B³ through its wall out-

wardly, said orifices being arranged in a horizontal plane discharging radially from the chamber, and through them the vapor is discharged in jets and is ignited on the outer side of the chamber. The tip B is formed with four radial arms B⁴ B⁵ B⁶ B⁷, extending horizontally from its base, and we provide the shield C, so named from its function, as hereinafter explained, which is a hollow cylinder having an opening through its base large enough to allow it to be passed down over the upper end of the burner-tip, and which rests upon the four radial arms B⁴ B⁵ B⁶ B⁷. The base C' of the shield C is perforated, said perforations c' being distributed over its entire surface and designed to admit air freely into it from below. Its cylindrical wall is pierced by apertures c², equal in number and in line radially with the orifices b³, respectively leading from the spreading-chamber B³.

Through the arms B⁴ and B⁵ holes are drilled into the ducts B' and B², respectively, and screw-valves D and E, suitably guarded about their stems with stuffing-boxes D' and E', are provided; entering through said holes and seating across said ducts B' and B², respectively. Directly above each of these valves simple screw-valves F and G are inserted through the arms D⁴ and D⁵, respectively, and seated in and adapted to close the ducts B' and B², respectively, above the seats therein of the valves D and E, respectively. These latter valves F and G are preferably made with slender tapering points, and their seats are of course similarly formed, whereby they are adapted to be very accurately adjusted. The valves D and E may not be so slender, but may cease more abruptly. The valve D we prefer to provide with a sheave-handle D', to which a chain H may be connected for convenience in operating it. The valve E may have no handle at all, or may be provided with a handle E'', as shown; but the valves F and G are preferably without handles, but may be slotted at the exposed ends to be operated by a screw-driver. These latter valves are designed to be so tightly fitted in their threads as to require no stuffing-boxes, and to be adjusted not too easily even by means of a screw-driver, and incapable of adjustment by the fingers without a tool.

This burner is designed to be used in the following manner: The valve E being closed and the valves F and D being open and the valve G either open or closed, it being at this 5 stage a matter of indifference whether it is open or closed, the fluid admitted through the pipe A and contained in the porous material A' flows up through the duct B', and, overflowing in the chamber B² and flowing 10 out through the orifices b³, will be ignited upon the outside of the burner-tip. It will be understood that for this purpose the shield C may be temporarily removed. The valve D may now be closed, or so nearly closed as 15 to admit a very slight quantity of oil past it, the oil which has overflowed and such additional quantity, if any, as may be supplied past the valve D burning freely until the entire burner-tip B and the tube A, connected 20 to it, are sufficiently heated to cause the fluid contained in the porous contents A' of the tube A to be vaporized therein, so that the discharge from the orifices b³ is no longer oil, but vapor. It will be understood that if the 25 valve D has been closed entirely after the first discharge of oil past it, as described, it must be opened again before the oil so discharged is entirely burned up, in order that the vapor or vaporized oil in the tube A may be admitted to 30 the burner-tip to maintain the flame. The valve D will now be opened wide, and the valve F will be screwed in until the discharge of vapor past it is limited to such amount as can be continuously generated in the chamber A. 35 This amount and the consequent adjustment of the valve F will be determined by the judgment of an expert or by sufficient experiment to ascertain it reliably, and the valve F, having been once set at this position, need 40 never be changed, except when a different grade of oil is to be used, which may change the conditions. The valve D being now closed entirely, and the valve E opened wide, the valve G will be adjusted to such position 45 that it will admit past it only the least quantity of vapor, which will maintain the temperature of the burner at the vaporizing-point. This valve, being thus adjusted, will need no change unless a different character 50 of oil is to be used, which may require a greater volume to maintain the same temperature, or which vaporizes at a different temperature. It will be seen that when the valves F and G are thus adjusted the flame may be 55 increased from the minimum which can be maintained to the maximum that the burner is capable of supplying reliably by opening the valve D to any desired extent, and that, once lighted and properly adjusted, the flame 60 will never be extinguished entirely, and the burner may therefore be operated with as great convenience as a burner fed by a gas-supply and provided with automatic lighting attachments, so that the process of first flooding 65 the burner with oil and watching it until it begins to vaporize and then with care requiring an expert adjusting it to the proper

point each time it is used is dispensed with. If at any time it is desired to extinguish the burner entirely, as when the light is not to 70 be required for a long time, as for several days or weeks, the valve E will be closed as well as the valve D; but in the ordinary intervals of use from night to night the valve E will be left open and the flame maintained 75 at the minimum, controlled by the valve G, as described.

It will be apparent that the slight flame formed when the valve D is closed and the vapor is admitted only past the minimum 80 valve G would be liable to be extinguished by drafts of air, and also that the large flame might be rendered unsteady and might be extinguished at some of the orifices momentarily by air-blasts accidentally directed upon 85 it if no protection were afforded for the flame. To afford such protection is the purpose of the shield C. This shield has the bottom C' perforated, as already described, the intention being to admit an abundant supply of air to 90 the flame, but to so thoroughly break it up that it shall be distributed evenly and not at any time reduced to a blast at any one point. The shield entirely encircles the burner-tip and is closed at the top, and has the apertures 95 c², which are radially in line with the apertures b³ in the burner-tip B. The apertures c², however, are very much larger than the orifices b³, the latter being from one one-hundredth to one-fiftieth of an inch—that is, barely large 100 enough to admit a fine needle—while the former—the apertures c²—are from three-sixteenths to three-eighths of an inch in diameter. The jets emitted from the orifices b³ are directed toward the apertures c², and when the 105 supply-valve is opened to such an extent as to produce actual illumination from the burner these jets shoot out through the apertures c². When the burner is turned down—that is, when the valve D is closed, or nearly 110 so—and the quantity of vapor admitted is that which is permitted by the valve G, the jets barely protrude from the orifices b³, or at least do not extend far enough to be visible outside the shield C. In practice a bare blue 115 point of flame is visible at the orifices b³ when the supply of vapor is at the minimum as controlled by the valve G.

We claim—

1. In a vapor-burner, in combination with 120 the fluid-supply pipe and the burner-tip and a duct communicating from the supply-pipe to the tip, and the valve controlling such duct, the tip having peripheral jet-orifices in horizontal plane, through which the vapor is 125 emitted radially, and a shield encircling and covering such tip and having peripheral openings in a horizontal plane radially in line with the jet-orifices, respectively, and through which the flame can extend when 130 the controlling-valve is sufficiently opened, substantially as set forth.

2. In a hydrocarbon-burner, in combination with the supply-pipe and the burner-tip,

two ducts which communicate with the supply-pipe and the tip, a limiting-valve seating in each of said ducts, one of such valves being adjusted to the minimum and the other to 5 the maximum of the desired supply, the third valve controlling the duct which has the maximum limiting-valve, the burner-tip having peripheral jet-orifices in horizontal plane, through which the vapor is emitted radially, 10 and a shield C, encircling and covering such tip and having in a horizontal plane peripheral flame-orifices c^2 , which are radially in line with the jet-orifices, respectively, whereby the jets of flame emitted from the jet-orifices 15 are caused to extend out separately and divergently in a horizontal plane through said flame-orifices, substantially as set forth.

3. In a vapor-burner, in combination with the burner-tip having jet-orifices located in

a horizontal plane and discharging radially, a 20 shield encircling and covering such tip and inclosing a chamber between the tip and the shield, the latter having peripheral apertures in a horizontal plane in line radially with the jet-orifices, respectively, and larger than the 25 latter, whereby the flame formed at the jet-orifices is shielded from exterior currents of air until it is emitted through the shield-apertures, substantially as set forth.

In testimony whereof we have hereunto set 30 our hands, in the presence of two witnesses, at Denver, Colorado, this 11th day of April, 1890.

ISAAC E. BLAKE.
